UNITED STATES PATENT OFFICE.

WILLIAM LOUIS BESSOLO, OF SAN DIEGO, CALIFORNIA.

QUICK-ADJUSTABLE WRENCH.

Specification of Letters Patent.

Patented Oct. 28, 1919.

1,319,944.

Application filed May 8, 1919. Serial No. 295,045.

To all whom it may concern:

Be it known that I, WILLIAM LOUIS BESSOLO, a citizen of the United States, and a resident of San Diego, in the county of San Diego and State of California, have invented a new and useful Improvement in Quick-Adjustable Wrenches, of which the following is a specification.

My present invention relates generally to wrenches, and more particularly to a quick adjustable wrench, my object being the provision of a simple comparatively inexpensive construction including fixed and movable jaws, the former of which may be quickly adjusted toward and away from the movable jaw in applying the same to work, by means which also acts in part to secure pressure movement of the movable jaw toward the rigid jaw during the operative use of the wrench.

The above as well as the details of my present improvement will be apparent from the following description thereof, in which reference is made to the accompanying drawing, forming a part of this specification, and wherein:

Figure 1 is an elevation of my improved wrench.

Fig. 2 is a vertical sectional view through a portion thereof.

Fig. 3 is a similar view taken substantially on line 3—3 of Fig. 2 with the shank of the movable jaw removed.

Referring now to these figures, my invention proposes a wrench including a rigid jaw 10 opposed by a movable jaw 11, the former being fixed at one end of a rigid shank 12 to which, at an intermediate point, is secured a rectangular lever casing 13.

The movable jaw 11 is slidably disposed upon the shank 12 for adjustable movement between the casing 13 and the fixed head 10, and is pivotally connected at 14 to the outer end of its shank 15, the latter of which extends in parallel spaced relation to the fixed shank 12 for a portion of the length of the latter, and projects at its free end into the casing 13 at the relatively opposite side thereof as compared to the shank 12. The movable shank 15 has an enlargement 16 adjacent the movable jaw 11, controlled by a spring 17 so as to normally hold the shank 15 substantially at right angles to the movable jaw 11, it being noted that the movable shank 15 is provided with a longitudinal series of ratchet teeth 18 along one side

thereof, and has a laterally extending stud 19 provided with a mill head 20 and projecting through a slot 21 at the adjacent side of the casing 13 in order to form a handle whereby the movable jaw 11 may be manually adjusted in a ready and quick manner upon the shank 12 toward and away from the fixed head 10.

Within the casing 13, a lever 22 is fulcrumed at 23 and is of angular form, one end having a series of teeth 24 for engagement with the teeth 18 of the shank 15, and the opposite end of which is pivotally connected at 25 to one end of links 26, the opposite ends of which are pivotally connected at 27 to the outer extremity of a movable shank 28 extending along the fixed shank 12 and fulcrumed at 29 upon a lug 30 projecting laterally from the said fixed shank 12 at a point within the casing 13.

Thus it is obvious that in order to manually adjust the movable head 11, it is simply necessary for the operator to grasp the mill head 20 of stud 19 and move the shank 15 upon its pivot 14 out of engagement with the teeth 24 of the lever 22; and it is furthermore obvious that when the operator grasps the shanks 12 and 28, moving the latter toward the former when the wrench is in use, rocking movement of lever 22 upon its fulcrum 23 tends to further shift the movable jaw 11 toward the fixed jaw 10, and thus snugly and tightly engage the work between the jaws and into comparatively snug engagement with which the movable head was previously adjusted, as described.

It is obvious therefore, that my present construction provides a quick adjustable wrench, at once simple and inexpensive, and one which will be strong and durable as well as effective in use.

I claim:

1. A wrench comprising a fixed jaw, a fixed shank upon which said jaw is rigid, a movable jaw opposing the fixed jaw and having a sliding connection with the said rigid shank, a shank extending from the movable jaw, a rocking lever fulcrumed in connection with the fixed shank and adjustably engaging the said movable shank to shift the latter and the movable jaw in the direction of the length of the rigid shank, and into and out of connection with which said movable shank is manually shiftable for adjusting the movable jaw, and a lever

fulcrumed upon and extending along the rigid shank and having a connection at one end with said first named lever.

2. A wrench comprising a fixed jaw, a fixed shank upon which said jaw is rigid, a movable jaw opposing the fixed jaw and having a sliding connection with the said fixed shank, a shank pivoted to and extending from the movable jaw and having a longitudinal series of teeth, a toothed lever fulcrumed in connection with the fixed shank and engaging the toothed portion of the movable shank to shift the latter in the direction of the length of the fixed shank and into and out of engagement with which the said movable shank is shiftable upon its pivot, and a lever fulcrumed upon and working toward and away from the fixed shank and having a pivotal connection at one end with the first named lever, for the purpose described.

3. A wrench comprising a fixed jaw, a fixed shank upon which said jaw is rigid, a lever casing secured to the fixed shank at a point intermediate the ends of the latter, a movable jaw opposing the fixed jaw and slidably mounted upon the fixed shank between the fixed jaw and the said lever casing, a movable shank pivoted to the movable jaw and normally extending parallel to the fixed shank and projecting within said lever casing, said movable jaw having a longitudinal series of teeth, an angular lever fulcrumed within the lever casing and having teeth at one end for engagement with the teeth of the movable shank, said movable shank having a laterally and exteriorly

projecting stud forming a handle whereby it may be moved on its pivot into and out of engagement with the said toothed lever, a second lever fulcrumed upon the fixed shank and extending therealong, and links pivotally connecting the first and second levers and arranged within the lever casing, for the purpose described.

4. A wrench comprising a fixed jaw, a fixed shank upon which said jaw is rigid, a lever casing secured to the fixed shank at a point intermediate the ends of the latter, a movable jaw opposing the fixed jaw and slidably mounted upon the fixed shank between the fixed jaw and the said lever casing, a movable shank pivoted to the movable jaw and normally extending parallel to the fixed shank and projecting within said lever casing, said movable jaw having a longitudinal series of teeth, an angular lever fulcrumed within the lever casing and having teeth at one end for engagement with the teeth of the movable shank, said movable shank having a laterally and exteriorly projecting stud forming a handle whereby it may be moved on its pivot into and out of engagement with the said toothed lever, a second lever fulcrumed upon the fixed shank and extending therealong, links pivotally connecting the first and second levers and arranged within the lever casing, for the purpose described, and a spring carried by the movable jaw and engaging the movable shank to normally hold the latter in engagement with the said toothed lever.

WILLIAM LOUIS BESSOLO.
